DESIGN.

—
J. BAUMGARTEN.
WALL PAPER.

No. 16,454.

Patented Jan. 12, 1886.

UNITED STATES PATENT OFFICE.

JOSEPH BAUMGARTEN, OF NEW YORK, N. Y., ASSIGNOR TO THE MANHATTAN WALL PAPER COMPANY, OF SAME PLACE.

DESIGN FOR WALL-PAPER.

SPECIFICATION forming part of Design No. 16,454, dated January 12, 1886.

Application filed September 18, 1885. Serial No. 177,503. Term of patent 3½ years.

To all whom it may concern:

Be it known that I, JOSEPH BAUMGARTEN, a citizen of the United States, and a resident of New York, in the county of New York and State of New York, have invented and produced a new and original Design for Wall-Paper, of which the following is a specification.

My design is especially adapted for wall decorations; and it consists in the novel features hereinafter described, and shown in the accompanying illustration, which is a face view of my design.

Similar letters indicate similar parts.

10 The letter A designates the web of wall-paper, and B the representation of a fisherman's seine or net spread out as when in use, composed of meshes a.

15 C indicates ropes or cables, having the usual 20 handles or floats, E.

D designates a crab, F a fish, H a marine plant, and I a flower, conventionalized.

The leading feature of my design is the seine or net, made with or without the usual concomitants of cables or ropes, and so arranged that the general effect on the wall will be the representation of a net spread out as when in use, and as having in it conventionalized marine plants, flowers, and fish.

25 I claim—

30 The design for wall-paper herein shown and described, the same consisting of the representation of a fisherman's net or seine, and having in it conventionalized marine plants, flowers, and fish.

JOSEPH BAUMGARTEN.
